(57) **CLAIM**

The ornamental design for a device for transporting a biological sample, as shown and described.

DESCRIPTION

FIG. 1 is a top, front, and left side perspective view of a device for transporting a biological sample.

FIG. 2 is a bottom, back, and right side view of the device of FIG. 1.

FIG. 3 is a left side view of the device of FIG. 1.

FIG. 4 is a right side view of the device of FIG. 1.

FIG. 5 is a front view of the device of FIG. 1.

FIG. 6 is a back view of the device of FIG. 1.

FIG. 7 is a top view of the device of FIG. 1; and,

FIG. 8 is a bottom view of the device of FIG. 1.
